PLASMA PROCESSING APPARATUS AND PLASMA PROCESSING METHOD

CROSS-REFERENCE TO RELATED APPLICATIONS

The present application is based on and claims priority from Japanese Patent Application No. 2022-109300, filed on Jul. 6, 2022, with the Japan Patent Office, the disclosure of which is incorporated herein in its entirety by reference.

TECHNICAL FIELD

The present disclosure relates to a plasma processing apparatus and a plasma processing method.

BACKGROUND

A technique is known in which a vertical type plasma processing apparatus is provided with a plasma partition wall so as to cover an opening formed in a sidewall of a processing container and plasma is generated in an internal space covered with the plasma partition wall (see, e.g., Japanese Patent Laid-Open Publication No. 2019-207913). In Japanese Patent Laid-Open Publication No. 2019-207913, parallel-plate type plasma electrodes are arranged on a pair of opposite sidewalls of the plasma partition wall, and at least regions of the plasma partition wall corresponding to the plasma electrodes are made of synthetic quartz.

SUMMARY

A plasma processing apparatus according to an aspect of the present disclosure includes a processing container having an opening in a sidewall, a partition wall that covers the opening and defines an internal space communicating with an inside of the processing container, an internal electrode that passes through the partition wall, is detachably and airtightly inserted into the internal space, and is supplied with RF power, and an external electrode provided outside the partition wall.

The foregoing summary is illustrative only and is not intended to be in any way limiting. In addition to the illustrative aspects, embodiments, and features described above, further aspects, embodiments, and features will become apparent by reference to the drawings and the following detailed description.

BRIEF DESCRIPTION OF THE DRAWINGS

FIG. 1 is a schematic view illustrating a plasma processing apparatus according to an embodiment.

FIG. 2 is a horizontal cross-sectional view illustrating the plasma processing apparatus according to the embodiment.

FIG. 3 is a cross-sectional view illustrating an example of a plasma generator.

FIG. 4 is a schematic view illustrating an example of an internal electrode and an external electrode.

FIG. 5 is a flowchart illustrating a plasma processing method according to the embodiment.

FIG. 6 is a horizontal cross-sectional view illustrating a plasma processing apparatus according to a modification of the embodiment.

DETAILED DESCRIPTION

In the following detailed description, reference is made to the accompanying drawings, which form a part thereof. The

2

illustrative embodiments described in the detailed description, drawings, and claims are not meant to be limiting. Other embodiments may be utilized, and other changes may be made without departing from the spirit or scope of the subject matter presented here.

Hereinafter, non-limiting exemplary embodiments of the present disclosure will be described with reference to the accompanying drawings. In all the accompanying drawings, the same or corresponding members or components will be denoted by the same or corresponding reference numerals, and redundant descriptions thereof will be omitted.

[Plasma Processing Apparatus]

A plasma processing apparatus 1 according to an embodiment will be described with reference to FIGS. 1 to 4. In the following, “synthetic quartz” means synthetic silica glass that is synthesized by oxidizing high-purity silicon tetrachloride ($SiCl_4$). Further, “natural quartz” means fused quartz glass (electrical fusion and flame fusion) obtained by melting natural quartz powder. Further, a combination of synthetic quartz and natural quartz is called silica glass.

The plasma processing apparatus 1 is a batch type apparatus that processes a plurality of (e.g., 50 to 200) substrates W at once. The substrates W are, for example, semiconductor wafers such as silicon wafers. The plasma processing apparatus 1 includes a reactor 10, a gas supply 30, a plasma generator 40, an exhauster 50, a heater 60, and a controller 90.

The reactor 10 has a cylindrical shape with an open lower end and a ceiling. The inside of the reactor 10 may be depressurized. The reactor 10 functions as a processing container that accommodates therein the plurality of substrates W arranged in multiple tiers. The reactor 10 is made of, for example, quartz.

A bottom flange 11 is formed at the lower end of the reactor 10. The bottom flange 11 is supported by a metal flange 21. The metal flange 21 is provided so as to sandwich an outer edge of the bottom flange 11 therebetween via a sealing member 22 such as an O-ring. The metal flange 21 is made of, for example, stainless steel. A lid 12 is airtightly attached to a lower surface of the bottom flange 11 via a sealing member 13 such as an O-ring. Thus, an opening at the lower end of the reactor 10 is airtightly closed. The lid 12 is made of, for example, stainless steel. A rotary shaft 15 is provided through a central portion of the lid 12 via a magnetic fluid seal 14. The rotary shaft 15 is rotatable relative to the lid 12. The lid 12 and the rotary shaft 15 may move up and down relative to the reactor 10. A turntable 16 is provided at an upper end of the rotary shaft 15. A boat 18 is placed on the turntable 16 with a heat insulating cylinder 17 interposed therebetween. The heat insulating cylinder 17 and the boat 18 are made of, for example, natural quartz. The heat insulating cylinder 17 prevents heat radiation from the opening at the lower end of the reactor 10. The boat 18 may move up and down in conjunction with the lid 12. The boat 18 is rotatable in conjunction with the rotary shaft 15. The boat 18 holds the plurality of substrates W arranged in multiple stages in the vertical direction.

A sidewall of the reactor 10 is provided with a rectangular opening 19 in the longitudinal direction (vertical direction) thereof. A length of the opening 19 in the vertical direction is the same as or longer than a length of the boat 18, so that the boat 18 and the opening 19 are formed so as to extend in the vertical direction, respectively. The opening 19 is covered with a partition wall 41 to be described later. The partition wall 41 defines an internal space P. The internal space P communicates with the inside of the reactor 10 through the opening 19.

An exhaust port **20** is provided at a lower portion of the sidewall of the reactor. The inside of the reactor **10** is emptied through the exhaust port **20** by the exhauster to be described later.

The gas supply **30** includes a raw material gas supply **31** and a reaction gas supply **32**.

The raw material gas supply **31** includes a raw material gas supply pipe **31a** inserted into the reactor **10** and has a raw material gas supply path **31b** outside the reactor. The raw material gas supply path **31b** is provided with a raw material gas source **31c**, a mass flow controller **31d**, and a valve **31e** in this order from upstream to downstream in a gas flow direction. Thus, the supply timing of a raw material gas from the raw material gas source **31c** is controlled by the valve **31e**, and the raw material gas is adjusted to a predetermined flow rate by the mass flow controller **31d**. The raw material gas is introduced into the raw material gas supply pipe **31a** from the raw material gas supply path **31b** and is discharged into the reactor **10** from the raw material gas supply pipe **31a**. The raw material gas may be, for example, a metal-containing gas or a silicon-containing gas. Examples of the metal-containing gas may include titanium tetrachloride ($TiCl_4$) gas. Examples of the silicon-containing gas may include dichlorosilane (DCS) gas.

The reaction gas supply **32** includes a reaction gas supply pipe **32a** inserted into the internal space **P** and has a reaction gas supply path **32b** outside the reactor **10**. The reaction gas supply path **32b** is provided with a reaction gas source **32c**, a mass flow controller **32d**, and a valve **32e** in this order from upstream to downstream in the gas flow direction. Thus, the supply timing of a reaction gas from the reaction gas source **32c** is controlled by the valve **32e**, and the reaction gas is adjusted to a predetermined flow rate by the mass flow controller **32d**. The reaction gas is introduced into the reaction gas supply pipe **32a** from the reaction gas supply path **32b** and is discharged into the internal space **P** from the reaction gas supply pipe **32a**. The reaction gas is a gas that reacts with the raw material gas to produce a reaction product, and may be, for example, a nitriding gas. Examples of the nitriding gas may include ammonia (NH_3) gas.

Each gas supply pipe (raw material gas supply pipe **31a** or reaction gas supply pipe **32a**) is made of, for example, natural quartz. The raw material gas supply pipe **31a** extends linearly in the vertical direction near an inner surface of the reactor **10**, is bent in an L-shape at a lower portion of the reactor **10**, passes through a side surface of the reactor and extends to the outside of the reactor **10**. The reaction gas supply pipe **32a** extends linearly in the vertical direction near an inner surface of the partition wall **41**, passes through a bottom surface of the partition wall **41**, and extends to the outside of the reactor **10**.

A plurality of raw material gas outlets **31f** are provided at a portion of the raw material gas supply pipe **31a** located inside the reactor **10**. A plurality of reaction gas outlets **32f** are provided at a portion of the reaction gas supply pipe **32a** located in the internal space **P**. Each outlet (raw material gas outlet **31f** or reaction gas outlet **32f**) is formed at a predetermined interval in a direction in which each gas supply pipe extends. Each outlet discharges the gas in the horizontal direction. The interval between the respective outlets is set to be equal to, for example, the interval between the substrates **W** held in the boat **18**. The position of each outlet in the height direction is set to an intermediate position between the substrates **W** adjacent to each other in the

vertical direction. Thus, each outlet may efficiently supply the gas to opposite surfaces between the adjacent substrates **W**.

The gas supply **30** may blend a plurality of types of gases and discharge a blend of the gases from one supply pipe. For example, the raw material gas supply pipe **31a** may be configured to be capable of discharging an inert gas to the inside of the reactor. For example, the reaction gas supply pipe **32a** may be configured to be capable of discharging an inert gas into the internal space **P**. The gas supply **30** may further include a supply pipe for supplying another gas in addition to the raw material gas supply pipe **31a** and the reaction gas supply pipe **32a**.

The plasma generator **40** includes the partition wall **41**, the introduction pipe **42**, an internal electrode **43**, an external electrode **44**, a seal unit **45**, and an RF power supply **46**.

The partition wall **41** is provided at a part of the sidewall of the reactor **10**. The partition wall **41** extends in a direction in which the plurality of substrates **W** are arranged. The partition wall **41** is airtightly welded to the sidewall of the reactor **10**. The partition wall **41** has a concave shape in horizontal cross section. The partition wall **41** covers the opening **19** and defines the internal space **P** communicating with the inside of the reactor **10**. The reaction gas supply pipe **32a** is provided in the internal space **P**. The partition wall **41** is made of, for example, natural quartz. The bottom surface of the partition wall **41** is provided with an introduction opening **41a** into which the internal electrode **43** is inserted.

The introduction pipe **42** is airtightly welded to the bottom surface of the partition wall **41**. The introduction pipe **42** is made of, for example, natural quartz. The introduction pipe **42** has a cylindrical shape, and is configured to cover the introduction opening **41a** and to communicate with the internal space **P** through the introduction opening **41a**.

The internal electrode **43** passes through the partition wall **41** and is detachably and airtightly inserted into the internal space **P**. The internal electrode **43** includes an insulating tube **43a** and a rod-shaped electrode **43b**.

The insulating tube **43a** has an elongated cylindrical shape with a sealed upper end. The insulating tube **43a** passes through the partition wall to be airtightly inserted into the internal space **P**, and extends in the direction in which the plurality of substrates **W** are arranged. The atmosphere inside the insulating tube **43a** may be, for example, the atmosphere or an inert gas. A pressure inside the insulating tube **43a** may be, for example, the atmospheric pressure. An outer diameter of the insulating tube **43a** is smaller than an inner diameter of the introduction opening **41a** and an inner diameter of the introduction pipe **42**. In this case, the insulating tube **43a** may be inserted into the internal space **P** with a gap with respect to the partition wall **41** and may be inserted into the introduction pipe **42** with a gap ther-

ebetween. A material of the insulating tube **43a** may be, for example, ceramics such as alumina, or natural quartz. The material of the insulating tube **43a** may be particularly natural quartz from the viewpoint of preventing ion damage due to a plasma when the substrate **W** is plasma-processed, or corrosion by a fluorine-based gas when the inside of the reactor **10** is dry-cleaned.

The material of the insulating tube **43a** may be more particularly made of synthetic quartz. Since the insulating tube **43a** provided in the internal space **P** is exposed to a plasma, it is damaged by sputtering or etching caused by ions in the plasma. In particular, when the plasma is gen-

erated from a gas that contains hydrogen but does not contain oxygen (e.g., ammonia gas or hydrogen gas), in addition to the damage caused by ions in the plasma, oxygen in silica glass is extracted by hydrogen, causing a structural change in a surface layer of the silica glass. Thus, a large distortion occurs in the silica glass, and the stress thereof may cause damage to the insulating tube 43a. Therefore, by using synthetic quartz, which is expected to have a denser microstructure and higher etching resistance than natural quartz, as the material of the insulating tube 43a, damage to the insulating tube 43a may be prevented. Further, the synthetic quartz may have an OH group concentration of 200 ppm or more. In this case, the stress generated in the synthetic quartz is reduced, and it is easy to prevent damage to the insulating tube 43a. Furthermore, in order to relieve the stress generated in the silica glass, the insulating tube 43a may have a circular or elliptical cross section perpendicular to a tube axis.

The rod-shaped electrode 43b has an elongated cylindrical shape and is inserted into the insulating tube 43a. The rod-shaped electrode 43b has a lower end which is pulled out from a lower end of the insulating tube 43a into the atmosphere and is connected to the RF power supply 46 via a feeder line and matcher (which are not illustrated). RF power is supplied from the RF power supply 46 to the rod-shaped electrode 43b. Since the rod-shaped electrode 43b is provided in the internal space P, it is used at a plasma processing temperature (e.g., 400° C.) or higher. A material of the rod-shaped electrode 43b may be a metal with low resistivity, and may employ copper or iron. However, since copper or iron has a high diffusion coefficient in natural quartz, a nickel alloy with high heat resistance and oxidation resistance may be employed from the viewpoint of avoiding metal contamination to the inside of the reactor 10.

The external electrode 44 includes a first external electrode 44a and a second external electrode 44b. The first external electrode 44a and the second external electrode 44b each have an elongated rectangular plate shape, the longitudinal direction of which corresponds to the vertical direction. The first external electrode 44a and the second external electrode 44b are fixed to outer surfaces of sidewalls of the partition wall 41. The first external electrode 44a and the second external electrode 44b are arranged opposite to each other. In this case, when RF power is supplied to the internal electrode 43, a capacitively coupled plasma (CCP) is generated between the internal electrode 43 and the first external electrode 44a and between the internal electrode 43 and the second external electrode 44b. Therefore, the plasma may be generated in a wide range of the internal space P. However, the external electrode 44 may include only one of the first external electrode 44a and the second external electrode 44b. For example, the first external electrode 44a and the second external electrode 44b are grounded. In this case, damage caused by the plasma to an inner surface of the sidewall of the partition wall 41 may be prevented.

The seal unit 45 airtightly seals the gap at the lower end of the introduction pipe 42. The seal unit 45 includes an inner cylinder member 45a, a sealing member 45b, a sleeve 45c, and an outer cylinder member 45d.

The inner cylinder member 45a is provided through a bottom wall of the metal flange 21. The inner cylinder member 45a is integrally formed with, for example, the metal flange 21. The inner cylinder member 45a has a male threaded portion on an outer peripheral surface thereof.

The sealing member 45b is provided between the insulating tube 43a, the sleeve 45c and the bottom flange 11. The sealing member 45b is, for example, an O-ring.

The sleeve 45c is inserted inside the inner cylinder member 45a. The sleeve crushes the sealing member 45b at an upper end thereof by moving upward. Thus, the sealing member 45b is pressed against three points including the insulating tube 43a, the sleeve 45c, and the bottom flange 11, so that the gap is airtightly sealed.

The outer cylinder member 45d has, on an inner peripheral surface thereof, a female threaded portion which is screwed to the male threaded portion of the inner cylinder member 45a. The sleeve 45c moves upward by screwing the female threaded portion of the outer cylinder member 45d to the male threaded portion of the inner cylinder member 45a. The outer cylinder member 45d is, for example, a nut.

The RF power supply 46 supplies RF power to the rod-shaped electrode 43b. Thus, the plasma is generated from the reaction gas supplied to the internal space P. The RF power has a frequency of, for example, 13.56 MHz.

The exhauster 50 includes an exhaust passage 51, a pressure regulating valve 52, and a vacuum pump 53. The exhaust passage 51 is connected to the exhaust port 20. The exhauster 50 regulates the pressure inside the reactor 10 by the pressure regulating valve 52 while evacuating the inside of the reactor 10 by the vacuum pump 53.

The heater 60 is provided around the reactor 10. The heater 60 includes a cylindrical heater chamber 61 with a ceiling and a heater wire 62 spirally wound on an inner surface of the heater chamber 61. The heater 60 heats each substrate W accommodated inside the reactor 10 by heat generated by the heater wire 62.

The controller 90 performs a plasma processing method to be described later, for example by controlling the operation of each part of the plasma processing apparatus 1. The controller 90 may be, for example, a computer. A computer program that performs the operation of each part of the plasma processing apparatus 1 is stored in a storage medium. The storage medium may be, for example, a flexible disk, compact disk, hard disk, flash memory, or DVD.

A plasma processing method performed using the plasma processing apparatus 1 according to the embodiment will be described with reference to FIG. 5. The plasma processing method according to the embodiment is performed by the controller 90 controlling the operation of each part of the plasma processing apparatus 1. In the following, a case of forming silicon nitride (SiN) film on the substrate W by plasma-enhanced atomic layer deposition (PEALD) as a plasma processing will be described by way of example.

First, the boat 18 holding the plurality of substrates W is lifted from below the reactor 10 and is loaded into the reactor 10 which is adjusted in advance to a predetermined temperature, and the opening at the lower end of the reactor 10 is closed by the lid 12, so that the inside of the reactor 10 is sealed. Subsequently, the inside of the reactor 10 is evacuated by the exhauster 50 to remain at a process pressure, and the substrate is raised in temperature by the heater 60 to remain at a process temperature. The boat 18 is rotated by rotation of the rotary shaft 15.

Next, the controller 90 performs steps S1 to S5 illustrated in FIG. 5 to form a SiN film on each substrate W.

In step S1, DCS gas is supplied to the inside of the reactor 10 from the raw material gas supply 31, so that the DCS gas is adsorbed onto each substrate W. In step S1, an inert gas may be supplied from the reaction gas supply 32 to the internal space P. In this case, the DCS gas supplied to the inside of the reactor 10 may be prevented from entering the internal space P.

Step S2 is performed after step S1. In step S2, while the inside of the reactor 10 is evacuated by the exhauster 50, an

inert gas is supplied from the raw material gas supply 31 to the inside of the reactor 10, and an inert gas is supplied from the reaction gas supply 32 to the internal space P. Thus, the DCS gas remaining inside the reactor 10 and in the internal space P is discharged. In step S2, evacuation of the inside of the reactor 10 by the exhaust 50, the supply of the inert gas from the raw material gas supply 31 to the inside of the reactor 10, and the supply of the inert gas from the reaction gas supply 32 to the internal space P may be performed alternately. In step S2, the inert gas may be supplied from only one of the raw material gas supply 31 and the reaction gas supply 32.

Step S3 is performed after step S2. In step S3, NH₃ gas is supplied from the reaction gas supply 32 to the internal space P, and RF power is applied from the RF power supply 46a to the internal electrode 43, so that a plasma is generated from the NH₃ gas in the internal space P. Active species contained in the generated plasma diffuse from the internal space P to the inside of the reactor 10, and the DCS gas adsorbed onto each substrate W is nitrified to form SiN film. In step S3, an inert gas may be supplied from the raw material gas supply 31 to the inside of the reactor 10. In this case, entry of active species into the raw material gas supply pipe 31a may be prevented. Therefore, it is possible to prevent the deposition of the SiN film inside the raw material gas supply pipe 31a.

Step S4 is performed after step S3. In step S4, while the inside of the reactor is evacuated by the exhaust 50, an inert gas is supplied from the raw material gas supply 31 to the inside of the reactor 10, and an inert gas is supplied from the reaction gas supply 32 to the internal space P. Thus, the NH₃ gas remaining inside the reactor 10 and in the internal space P is discharged. In step S4, evacuation of the inside of the reactor by the exhaust 50, the supply of the inert gas from the raw material gas supply 31 to the inside of the reactor 10, and the supply of the inert gas from the reaction gas supply 32 to the internal space P may be performed alternately. In step S4, the inert gas may be supplied from only one of the raw material gas supply 31 and the reaction gas supply 32.

Step S5 is performed after step S4. In step S5, it is determined whether or not steps S1 to S4 have been performed a set number of times. When the number of implementation times has not reached the set number of times (NO in step S5), steps S1 to S4 are performed again. Meanwhile, when the number of implementation times has reached the set number of times (YES in step S5), the film thickness of the SiN film has reached a target film thickness, so that the processing ends. In this way, a SiN film is formed on each substrate W by repeating steps S1 to S4 until the number of implementation times reaches the set number of times. The set number of times in step S5 is set according to, for example, the target film thickness of the SiN film. The set number of times in step S5 may be one time or a plurality of times.

As described above, according to the plasma processing apparatus 1 of the embodiment, there are provided the internal electrode 43, which passes through the partition wall 41 and is detachably and airtightly inserted into the internal space P and to which RF power is supplied, and the external electrode 44, which is provided outside the partition wall 41. By installing the electrode, to which RF power is supplied, in the internal space P in this manner, a surface of the detachable internal electrode 43, rather than the inner surfaces of the sidewalls of the partition wall 41, may be easily damaged by the plasma. Thus, it is possible to prevent the partition wall 41 from being distorted and damaged, so

that the lifespan of the partition wall 41 and the reactor 10 to which the partition wall 41 is welded may be prolonged. Further, the insulating tube 43a, which constitutes the internal electrode 43, is easily damaged by the plasma, but the internal electrode 43 may be attached to and detached from the partition wall 41. Therefore, only the insulating tube 43a needs to be replaced periodically, and the maintenance cost and environmental load may be reduced.

Meanwhile, consider a case where a pair of electrodes 10 (hereinafter referred to as "parallel plate electrodes") are arranged opposite to each other on outer surfaces of two sidewalls of the partition wall 41 defining the internal space P, and RF power is supplied between the parallel plate electrodes to generate a plasma in the internal space P. In this case, the inner surfaces of the sidewalls of the partition wall 41 are damaged by sputtering or etching caused by ions in the plasma. In particular, when the plasma is generated from a gas that contains hydrogen but does not contain oxygen (e.g., ammonia gas or hydrogen gas), in addition to the damage caused by ions in the plasma, oxygen in silica glass is extracted by hydrogen, causing a structural change in a surface layer of the silica glass. Thus, a large distortion occurs in the silica glass, and the stress thereof may cause damage to the insulating tube 43a. Thus, the lifespan of the partition wall 41 and the reactor 10 to which the partition wall 41 is welded is shortened.

[Modification of Plasma Processing Apparatus]

A plasma processing apparatus 1A according to a modification of the embodiment will be described with reference to FIG. 6. The plasma processing apparatus 1A illustrated in FIG. 6 differs from the plasma processing apparatus 1 in that there are two internal spaces P in which a plasma is generated. Other configurations may be the same as those of the plasma processing apparatus 1. Hereinafter, differences 30 from the plasma processing apparatus 1 will be mainly described.

The two internal spaces P are formed respectively by the partition wall 41. Two partition walls 41 are provided at different positions in the circumferential direction of the reactor 10. For example, the two partition walls 41 are provided so as to sandwich the raw material gas supply pipe 31a in the circumferential direction of the reactor 10.

The same effects as in the plasma processing apparatus 1 may also be obtained in the plasma processing apparatus 1A. 45 Three or more internal spaces P may be provided.

According to the present disclosure, damage to a partition wall may be prevented.

From the foregoing, it will be appreciated that various embodiments of the present disclosure have been described herein for purposes of illustration, and that various modifications may be made without departing from the scope and spirit of the present disclosure. Accordingly, the various embodiments disclosed herein are not intended to be limiting, with the true scope and spirit being indicated by the 50 following claims.

What is claimed is:

1. A plasma processing apparatus comprising:
a processing container having an opening in a sidewall;
a partition wall configured to cover the opening and define an internal space communicating with an inside of the processing container;
an internal electrode that passes through the partition wall, is detachably and airtightly inserted into the internal space through an introduction opening, and is supplied with RF power; and
an external electrode provided outside the partition wall.

2. The plasma processing apparatus according to claim 1, wherein the partition wall has an introduction opening into which the internal electrode is inserted,

the plasma processing apparatus further comprises an introduction pipe having a cylindrical shape that is fixed to the partition wall and communicates internally with the introduction opening, and the internal electrode is inserted into the introduction pipe.

3. The plasma processing apparatus according to claim 1, wherein the internal electrode includes an insulating tube having a cylindrical shape and a rod-shaped electrode inserted into the insulating tube.

4. The plasma processing apparatus according to claim 3, wherein the insulating tube is made of synthetic quartz.

5. The plasma processing apparatus according to claim 4, wherein the synthetic quartz has an OH group concentration of 200 ppm or more.

6. The plasma processing apparatus according to claim 3, wherein the insulating tube has a circular or elliptical cross section perpendicular to a tube axis.

7. The plasma processing apparatus according to claim 1, wherein the external electrode is grounded.

8. The plasma processing apparatus according to claim 1, wherein the external electrode is provided on each of two opposite side surfaces of the partition wall.

9. The plasma processing apparatus according to claim 1, further comprising:

a raw material gas supply configured to supply a raw material gas to the inside of the processing container; and

a reaction gas supply configured to supply a reaction gas into the internal space, the reaction gas reacting with the raw material gas.

10. The plasma processing apparatus according to claim 1, wherein the processing container is configured to accommodate a plurality of substrates arranged in multiple tiers, and

the partition wall and the internal electrode extend in a direction in which the plurality of substrates are arranged.

11. A plasma processing method comprising:

providing a plasma processing apparatus including:

a processing container having an opening in a sidewall; a partition wall configured to cover the opening and define an internal space communicating with an inside of the processing container;

an internal electrode that passes through the partition wall, is detachably and airtightly inserted into the internal space through an introduction opening, and is supplied with RF power; and

external electrode provided outside the partition wall, and performing a plasma processing on a substrate accommodated in the processing container, wherein the plasma processing includes generating plasma from a gas supplied to the internal space by applying the RF power to the internal electrode.

12. The plasma processing method according to claim 11, wherein the gas contains hydrogen.
